UNITED STATES PATENT OFFICE.

CHARLES TRAVIS HUPP, OF NEW MARKET, VIRGINIA.

DESIGN FOR A WIRE-FENCE-TWISTING DISK.

SPECIFICATION forming part of Design No. 19,308, dated September 10, 1889.

Application filed July 9, 1889. Serial No. 316,960½. Term of patent 14 years.

To all whom it may concern:

Be it known that I, CHARLES TRAVIS HUPP, a citizen of the United States, residing at New Market, in the county of Shenandoah and State of Virginia, have invented a new and useful Design for a Twister for Wire-Fence Machines, of which the following is a specification.

The invention relates to a new and original design for a twister for wire-fence machines.

The drawing is a perspective view of a twister showing my design.

The leading feature of the design is the circular or disk shape of the twister, having the perforations and notches shown. A circular or disk-shape twister B has a pivot-perforation b and peripheral grooves or perforations b' , arranged at equal distances from the perforation b , and provided with countersunk or beveled edges b^2 , and the said perforations

b' have openings extending transversely across the periphery of the disk. The disk b is provided with a central opening b^3 and similar smaller openings b^4 , arranged in the form of an equilateral triangle around the central opening. 25

What I claim is—

The new design for a wire-twister, comprising the disk having the perforation b , the peripheral perforations or grooves b' , having 30 countersunk or beveled edges b^2 , the central openings b^3 , and the triangularly-arranged openings b^4 , substantially as described.

In testimony that I claim the foregoing as my own I have hereto affixed my signature in 35 presence of two witnesses.

CHARLES TRAVIS HUPP.
